UNITED STATES PATENT OFFICE

147,979

DESIGN FOR A DISPLAY FIXTURE

Holmes E. Jones, Beaumont, Tex.

Application June 7, 1946, Serial No. 130,504

Term of patent 3½ years

(Cl. D80—9)

To all whom it may concern:

Be it known that I, Holmes E. Jones, a citizen of the United States, residing at Beaumont, in the county of Jefferson and State of Texas, have invented a new, original, and ornamental Design for a Display Fixture, of which the following is a specification, reference being had to the accompanying drawing, forming a part thereof.

Figure 1 is a perspective view of a display fixture showing my new design; and

Figure 2 is a perspective view of the same taken from an opposite point of view.

I claim:

The ornamental design for a display fixture, as shown.

HOLMES E. JONES.
